UNITED STATES PATENT OFFICE.

JAMES BAXTER HUTCHISON, OF BUTTE CITY, MONTANA.

CONDENSER FOR STEAM-ENGINES.

SPECIFICATION forming part of Letters Patent No. 439,664, dated November 4, 1890.

Application filed May 29, 1890. Serial No. 353,655. (No model.)

To all whom it may concern:

Be it known that I, JAMES BAXTER HUTCHISON, a citizen of the United States of America, residing at Butte City, in the county of Silver Bow and State of Montana, have invented certain new and useful Improvements in Condensers for Steam-Engines, of which the following is a specification, reference being had therein to the accompanying drawing.

The nature and object of my invention consist in exhausting the steam from the steam-cylinder into the suction or supply pipe of the pump and in providing such supply-pipe with an exhaust-nozzle connected with the exhaust-pipe, and in the utilization of the steam from the exhaust-pipe to assist in raising water in the supply-pipe. I attain these objects by the mechanism illustrated in the accompanying drawing, in which the figure is 20 a side elevation of my device, the nozzle-joint being shown partly in section.

The connections with the engine and pump are shown without letters of reference.

25 A is the exhaust-pipe leading from the steam-cylinder directed toward the reservoir G at the joint B and connected with the nozzle-joint E of the supply-pipe H at the joint C, leading into the end of the supply-pipe H at its end most remote from the pump beneath the surface of the water in the reservoir G. The nozzle-joint E of the supply-

35 pipe H is enlarged and perforated to admit the inflow of water. Projecting inwardly from its end is the exhaust-nozzle F, which may be cast integrally therewith, being gradually reduced in diameter, forming the orifice of escape, so as to secure pressure of the steam and project it into the water running into the supply-pipe toward the pump. The effect of this construction and arrangement of parts 40 is to assist the lifting of water by pressure of the steam, and at the same time give a better vacuum than is formed by exhausting into the open air, and also to avoid the inconvenience incident to exhaust-steam in a confined space. 45

Having thus described my invention, what I claim, and desire to secure by Letters Patent, is—

50 In combination with the exhaust-steam pipe A, leading into the extreme end of the supply-pipe of the pump beneath the surface of the water and having the enlarged perforated nozzle E, and the inwardly-projecting exhaust-nozzle F, gradually reduced in its diameter at the orifice of escape, as and for the 55 purposes described and shown.

In testimony whereof I affix my signature in presence of two witnesses.

JAMES BAXTER HUTCHISON.

Witnesses:

JNO. L. POLEN,
WILLIAM T. CATON.

Correction in Letters Patent No. 439,664.

It is hereby certified that in Letters Patent No. 439,664, granted November 4, 18
upon the application of James Baxter Hutchison, of Butte City, Montana, for an
provement in "Condensers for Steam-Engines," an error appears in the printed spec
cation requiring correction, as follows: In line 53, the word "and" should be strik
out; and that the Letters Patent should be read with this correction therein that
same may conform to the record of the case in the Patent Office.

Signed, countersigned, and sealed this 18th day of November, A. D. 1890.

CYRUS BUSSEY,
Assistant Secretary of the Inter

Countersigned:

C. E. MITCHELL,
Commissioner of Patents.
